(57) **CLAIM**

The ornamental design for an animal training tool, as shown and described.

DESCRIPTION

FIG. 1 is a perspective view of an animal training tool, showing our new design.

FIG. 2 is a front view of the animal training tool of FIG. 1. FIG. 3 is a rear view of the animal training tool of FIG. 1. FIG. 4 is a right side view of the animal training tool of FIG. 1.

FIG. 5 is a left view of the animal training tool of FIG. 1. FIG. 6 is a top view of the animal training tool of FIG. 1; and,
FIG. 7 is a bottom view of the animal training tool of FIG. 1.

The evenly dotted broken lines in the figures illustrate unclaimed features of the animal training tool that form no part of the claimed design. The dash-dot-dash broken lines in the figures define boundary lines that form no part of the claimed design.
